UNITED STATES PATENT OFFICE

FREDERICK KOEHLER, OF CHICAGO, ILLINOIS

JACK FOR RAISING TRUCK FRAMES

Application filed May 25, 1931. Serial No. 539,815.

This invention relates to jacks for raising truck frames and has for its principal objects to produce a jack for lifting the side frame in which all possibility of slipping is eliminated and all danger of collapse averted; to eliminate the need of chains, hooks and anchoring tackle and to produce a simple, relatively light and movable jack which may be slid under the truck frame and be securely anchored by its engagement with the head of the rail.

These and other objects and advantages of the invention will become apparent from the specification and the drawing, in which

Fig. 1 is an elevation showing the jack properly placed under the side frame of a railway car;

Fig. 2 is a top plan view of the jack;

Fig. 3 is a side elevation showing the jack in lowered position;

Fig. 4 is a side elevation showing the jack in the raised position.

The construction of a railway car journal is such that the journal brasses may only be removed when the truck side frame has been lifted sufficiently to allow them to be withdrawn over the car axle. The side frame must be jacked up whenever the journal brasses are to be renewed and it is distinctly advantageous to jack up the side frame and remove the journal brasses in order to inspect the bearings in a thoroughgoing manner. Previously, jacks which have been used are adaptations of the well-known Barrett type and have required that a yoke or anchor be used which engages the wheel in order to keep the raising bar from slipping. Not only is this a relatively clumsy contrivance which does not lend itself well to maintenance work, but there is considerable danger that the anchors may slip and seriously injure the workmen. These defects are eliminated in the apparatus which I now propose.

The jack, generally indicated by 10, is composed of two spaced web elements 11 and 12 which bear out-turned portions 13 and 14 bent to engage the foot plate 15. The webs are anchored to the foot plate by the bolts 16.

A block 17 held between the webs by the bolts 18 spaces the web at the opposite end.

Two levers are pivoted on the webs, one, a raising bar 19 is pivoted at 21 on the pin 22 and the other, a cranked lever 23, is pivoted at 24 on the bolt 25. As is best shown in Fig. 3, the operating lever is so placed that its working arm 26 lies beneath the raising bar 19. Its end is slotted at 27 and bears a roller 28 fitted therein which is journaled on the pin 29.

The pressure receiving arm 31 of the operating lever is forged or machined into a cylindrical form in order that a pipe extension handle 32 may be slid thereover. The stop 33, attached to the foot plate 15, engages the arm 31 just after the arm 26 has passed dead center and thus locks the jack almost in its maximum elevated position. The pin 22 may be formed with the extension head 35 thereon to form a handle which is useful in placing or removing the jack.

An important element of this invention is found in the projections or claws 34 which I prefer to form integrally with the webs at their inner ends. These are adapted to engage the inner face of the head of the rail and prevent the jack from moving or slipping laterally.

In operation, the inner end of the jack is slid under the lowermost and approximately the central portion of the side frame and allowed to rest upon the rail with the projections 34 engaging the head. The outer end is held up by adjustable blocking, as shown at 37 in Figs. 3 and 4, a procedure which is necessary because of the irregularities in the roadbed.

When the upper margins of the webs are approximately level, the pipe 32 is then pulled away from the car which causes the work arm 26 of the operating lever to rise and carry with it the raising bar 19. This, as is indicated in Figs. 3 and 4, engages the side frame 36 and raises it.

Also, as is indicated by the figures, the working arm 26 has lifted the raising bar to its maximum, passed on through a slight angle and dropped the bar slightly. In other

words, it is intended that the operating lever shall pass dead center and, in consequence, the jack is firmly locked in the raised position whenever the operating lever is pushed 5 down to such an extent that the arm 31 engages the stop 33. With the side frame in the raised position, the journal brasses are freed and may then be removed or inspected.

It will thus be seen that I have produced a 10 simple, rugged, relatively light, portable jack which may be slid under the side frames without difficulty and which cannot slide laterally since it is rigidly held by the rail. Since a single unit is used, no relative motion is 15 possible. The claws and the single rigid base perform all the functions of the anchoring tackle previously used.

This is an important contribution to safety 20 over methods which require some yoke or harness, which always involves the danger that the tackle may slip or that the jack may buck.

What I claim, therefore, is:

1. A jack for raising car truck frames comprising a base, a lever pivoted to the base 25 adapted to be raised therefrom to engage and lift a car truck frame, a foot portion provided on the base near the pivot of the lever formed to be received over a rail and prevent 30 lateral movement between the jack and the rail, and another foot portion provided on the base spaced from the first foot and positioned in a horizontal plane lower than that 35 of the first foot adapted to receive an adjustable support placed on the roadway, in combination with means for rotating said lever about its pivot.

2. A jack for raising car truck frames comprising a base, a lever pivoted to the base 40 adapted to be raised therefrom to engage and lift a car truck frame, a foot portion provided on the base below the horizontal plane of the pivot point formed to be received over 45 a rail and prevent lateral movement between the jack and the rail, and another foot portion provided on the base spaced from the first foot and positioned in a still lower horizontal plane adapted to receive an adjustable support placed on the roadway, in combination 50 with means for rotating said lever about its pivot.

3. A jack as claimed in claim 1 in which the base includes a pair of substantially L-shaped webs secured together, the end of the 55 horizontal portion of each web is provided with a projection for engaging the head of a rail, and the end of the vertical portion is provided with a lateral flange for engaging an adjustable support on the roadway.

60 4. A jack as claimed in claim 1 in which the truck frame engaging lever is pivoted on the base between the spaced foot portions thereof.

65 5. A jack for lifting a car truck frame including a base provided with spaced foot

portions adapted to be supported by a rail and a portion of the roadway respectively, a raising bar pivoted on the base adapted to engage the truck frame, a cranked primary lever pivoted on the base having an arm 70 adapted to engage and lift the raising bar, and a stop formed on the base adapted to be engaged by a portion of the cranked lever after passing dead center, whereby the jack is locked in raised position.

In testimony whereof I affix my signature.

FREDERICH KOEHLER.
